(57) **CLAIM**

The ornamental design for a cabin as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front-left perspective view of a cabin according to the claimed design.

FIG. 2 is a left side view of the cabin.

FIG. 3 is a rear-left perspective view of the cabin.

FIG. 4 is a rear-right perspective view of the cabin.

FIG. 5 is a front-right perspective view of the cabin; and,

FIG. 6 is a top-left perspective view of the cabin.

Any reflection or shadowing in the drawings forms no part of the claimed design.
